(57) **CLAIM**

The ornamental design for a bottle as shown and described.

DESCRIPTION

FIG. 1 is a top, back and left perspective view of a bottle, showing our new design;

FIG. 2 is an elevational view of the front side thereof;

FIG. 3 is an elevational view of the back side thereof;

FIG. 4 is an elevational view of the left side thereof;

FIG. 5 is an elevational view of the right side thereof;

FIG. 6 is a top plan view thereof; and,

FIG. 7 is a bottom plan view thereof.

The broken lines, the areas within them, and the unshaded areas bounded by broken lines and solid lines depict portions of the bottle that form no part of the claimed design.
